US0D1028091S

(12) **United States Design Patent** (10) Patent No.: **US D1,028,091 S**
(45) Date of Patent: ** May 21, 2024

(54) **PEN CLIP**

(71) Applicant: **Chuanhui Wang**, Sanming (CN)

(72) Inventor: **Chuanhui Wang**, Sanming (CN)

(**) Term: **15 Years**

(21) Appl. No.: **29/840,543**

(22) Filed: **May 31, 2022**

(51) LOC (14) Cl. **19-06**

(52) U.S. Cl.

USPC **D19/202**; D19/99

(58) **Field of Classification Search**

USPC D19/37, 38, 65, 99, 100; D15/138, 140
CPC B23K 9/26; B23K 9/013; B23K 9/164;

B08B 5/02

See application file for complete search history.

(57) **CLAIM**

The ornamental design for a pen clip, as shown and described.

DESCRIPTION

FIG. 1 is a front view of the pen clip;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines in the figures represent portions of the pen clip that form no part of the claimed design.

1 Claim, 7 Drawing Sheets
